(57) **CLAIM**

The ornamental design for an inventory-tracking robotic system, as shown and described.

DESCRIPTION

FIG. 1 is a front elevation view of an inventory-tracking robotic system.

FIG. 2 is a rear elevation view of the inventory-tracking robotic system.

FIG. 3 is a left side elevation view of the inventory-tracking robotic system.

FIG. 4 is a right side elevation view of the inventory-tracking robotic system.

FIG. 5 is a bottom plan view of the inventory-tracking robotic system.

FIG. 6 is a top plan view of the inventory-tracking robotic system.

FIG. 7 is a rear lower left isometric view of the inventory-tracking robotic system; and,

FIG. 8 is a front upper right isometric view of the inventory-tracking robotic system.

Some broken lines shown in the FIGURES depict environmental structure. Other broken lines shown in the FIGURES depict alternative surfaces of portions of the inventory-tracking robotic system. However, no broken line shown in the FIGURES forms any part of the design claimed in the instant Application.
